GARMENT PROTECTING ATTACHMENT FOR
GARMENT HANGERS

Louise M. Jacomini, Hermosa Beach, Calif.

Application April 28, 1947, Serial No. 744,462

3 Claims. (Cl. 223—92)

1

This invention relates to a garment protecting attachment for garment hangers of the usual type, that is, a hanger comprising a curved supporting arm provided with a centrally disposed suspension hook.

An object of the invention is to provide a simple device adapted to be readily attached to an ordinary garment hanger of the type above stated, which will keep the neck portion of a garment supported thereon from coming into contact with the suspension hook and being wrinkled and misshapen thereby.

A further object of the invention is to provide a device as mentioned, particularly adapted for protecting dresses made of light and soft materials.

A further object of the invention is to provide a protective attachment of the class stated, which will hold the neck portion of the garment out of contact with the suspension hook, and yet permit the hanger supported garments to be crowded together in limited spaces.

A further object of the invention is to provide a device as mentioned which shall be of low cost to manufacture.

Other objects will appear hereinafter.

The invention will be more readily understood by reference to the accompanying drawings forming a part of this application and in which:

Figure 1 is a front elevation of a hanger equipped with an attachment embodying my invention,

Figure 2 is a plan view thereof,

Figure 3 is an end elevation of the same,

Figure 4 is a plan view of the attachment before applying the same to the hanger,

Figure 5 is a similar view of a modified form of the invention, consisting of a plurality of layers of material, with portions of the upper layers broken away, and

Figure 6 is a section on the line 6—6 of Figure 5.

Referring to the drawings, 10 indicates the curved arm of a garment hanger of the usual type. This is usually formed of wood and provided with a centrally disposed wire suspension hook 11.

The attachment comprises a blank 12 formed of a sheet of flexible material such as stiff resilient paper; although the invention is not confined to the use of paper as will appear hereinafter.

The blank 12 comprises an elongated body portion having a straight upper edge 13 extending the greater portion of its length, and an arcuate, or curved lower edge 14. The body terminates at

2

the opposite ends in slightly downwardly extending lobes 15 having rounded edges 16. The outer edges 16 of the lobes merge with the straight top edge 13 by curves 17; and with the bottom edge 14 by reverse curves 18. The lobes 15 are each preferably provided adjacent the tip thereof with small perforation 19, for a purpose herein-after disclosed.

The device is applied to a hanger with the body 10 back of the hook 11 and with the straight edge 13 up. The end lobes 15 are then flexed forwardly over the arms 10 and secured to the front face of the hanger arm by any suitable means, such as by thumb tack 20 extending through the perforations 19 and into the wooden hanger arm. It should be noted that the reverse curve 18 at the lower edge engages over the top edge of the hanger and permits the protector to assume the desired shape without distortion; and also permits said lower edge to slide over the hanger arm as the pressure on the front and back varies.

When in position on the hanger, the device provides a smooth curved surface area for the neck portion of the garment and prevents it from coming into contact with the supporting hook. Also, the body portion normally slopes downwardly and outwardly as shown in Figure 3, to hold the adjacent portion of the garment in shape and prevent undue wrinkling.

Being formed of flexible, resilient material a plurality of hangers with the garments thereon may be crowded together in a rack to occupy a limited space, without injury to the dresses, and without the loss of the function for which the device is designed. When so crowded together, the rearward and downwardly sloping body portion will be merely pressed more closely to the hanger arm and will still function to maintain the neck of the garment smooth and out of contact with the hanger hook. Also, by attaching the device to the hanger arm in the manner described, the portions thereof forwardly of the hanger arm will curve outwardly and downwardly and then inwardly to the points of attachment, such as the tacks 20, thereby forming convex or outwardly arched surfaces to engage the garment with no projecting ends or edges to injure the same. This is desirable for home use, but is particularly advantageous in stores where the dresses are displayed in large numbers and crowded together on racks, where they are subjected to rough handling by the shoppers.

In Figures 5 and 6, a modified form of the invention is illustrated. As shown therein, the

device may be made of several layers of material, the outer layers 21 and 22 being formed of felt or other similar material to minimize slipping of the garment on the hanger, and an intermediate layer or sheet 23 of resilient material, the several layers being united by a row of stitching 24 close to the edge of the device. By this construction of the device, the felt face will prevent the garment from slipping on the hanger, which is particularly advantageous when used on display racks as hereinbefore mentioned. Also by having both faces of the device formed of frictional material, the device may be readily reversed on the hanger when found desirable.

While the preferred forms of the device have been illustrated and described herein, it is to be understood that modifications may be made therein without departing from the invention as set forth in the accompanying claims.

I claim:

1. An article of manufacture, a protective device for a garment hanger formed of a sheet of resilient material and comprising a body portion having a straight upper edge, an arcuate lower edge and oppositely extending end lobes having curved edges merging with the straight upper edge of the body and reversely curved edges merging with the arcuate lower edge thereof, each of said end lobes being provided with a perforation to receive means for attaching the device to a hanger arm.

2. A protective device for a garment hanger formed of a multi-ply sheet of material consisting of a resilient ply and an outer ply of frictional material, and comprising a body portion having a substantially straight upper edge and

an arcuate lower edge, and oppositely extending end lobes having curved edges merging into the upper and lower edges of the body portion, said lobes being provided with apertures to receive attaching means for securing the same to the hanger.

3. In a garment hanger, a curved arm and a supporting hook, in combination with a garment protective device formed of a sheet of resilient material and comprising a body portion arranged back of said hook and the adjacent portion of said arm, end lobes in continuation of said body, flexed over the hanger arm and attached to the front face of said arm, the upper edge of said body portion being straight when unflexed and the upper edges of said lobes merging into said straight upper edge, the lower edge of said body being arcuately curved downwardly, the lower edge of said body and said lobes being connected by reverse curves slidably engaging the upper edges of said arm.

LOUISE M. JACOMINI.
